BIS(N - HALOALKANOYL - PIPERIDYL)ALKANES AND BIS[N-(HALOALKANOYL - AMINOALKYL)- PIPERIDYL]ALKANES

Alexander R. Surrey, Albany, N.Y., assignor to Sterling Drug Inc., New York, N.Y., a corporation of Delaware
No Drawing. Filed Oct. 17, 1963, Ser. No. 317,079
8 Claims. (Cl. 260—294)

This invention relates to compositions of matter of the class of substituted piperidines.

The invention here resides in the concept of a composition of the molecular structure in which alkylene having from three to eight carbon atoms between its connecting linkages is attached through each of its two connecting linkages to a carbon atom of a piperidine ring bearing as an N-substituent halo-lower-alkanoyl attached directly or through aminoalkyl having from two to six carbon atoms. The N-substituents of the two piperidine rings can be the same or different and the points of attachment of the alkylene moiety to the piperidine ring-carbon atoms can be at any available position, e.g., 2, 3 or 4, and can be the same or different for the two piperidine rings.

The physical embodiments of the concept have been tested by standard chemotherapeutic evaluation procedures *in vivo* in hamsters and found to possess amebacidal activity.

Among the compounds of my invention are the dipiperidines of the Formula I

(I)

and those of Formula II

(II)

where Ac₁ and Ac₂ are each halo-lower-alkanoyl having from one to four carbon atoms and from one to three halogen atoms, Y is alkylene having from three to eight carbon atoms between its connecting linkages, X₁ and X₂ are each alkylene having from two to six carbon atoms and having at least two carbon atoms between its connecting linkages. Optionally, each piperidine ring can be substituted by lower-alkyl radicals, e.g., methyl, ethyl, n-propyl, and the like, at available ring-carbon positions.

In the above Formulas I and II, Y represents alkylene having from three to eight carbon atoms between its connecting linkages, illustrated by

and the like.

In the above Formula II, X₁ and X₂ can be the same or different and each has from two to six carbon atoms and has at least two carbon atoms between its connecting linkages, illustrated by

and the like.

2

Optionally, the above alkylene radicals represented by Y, X₁ and X₂ can be interrupted by O, S and carbon-to-carbon double bonds provided the O, S or double bond is not directly attached to either of the terminal 5 carbon atoms bearing the connecting linkages, e.g.,

In the above Formulas I and II, the halo-lower-alkanoyl radicals designated as Ac₁ and Ac₂ can be the same or different and each can have preferably from one to four carbon atoms and from one to three halogen atoms, as illustrated by chloroformyl (chloromethanoyl), chloroacetyl (chloroethanoyl), bromoacetyl, iodoacetyl, fluoroacetyl, dichloroacetyl, dibromoacetyl, diidoacetyl, difluoroacetyl, bromochloroacetyl, chlorofluoroacetyl, trichloroacetyl, tribromoacetyl, bromodichloroacetyl, chlorodibromoacetyl, dichlorofluoroacetyl, chloriodoacetyl, 2-chloropropanoyl (alpha-chloropropionyl), 3-chloropropanoyl (beta-chloropropionyl), 2-bromopropanoyl, 2,2-dichloropropanoyl, 2,2-diiodopropanoyl, 2,2-dibromo-
25 propanoyl, 2,2-difluoropropanoyl, 2,3-dichloropropanoyl, 2-bromo-3-chloropropanoyl, 2,2,3-trichloropropanoyl, 2-chlorobutanoyl (alpha-chlorobutyryl), 3-chlorobutanoyl, 4-chlorobutanoyl, 2,2-dichlorobutanoyl, 2,3-dibromobutanoyl, 2,2-dibromobutanoyl, 2,3,4-trichlorobutanoyl, 2,2,3-tribromobutanoyl, and the like.

The N,N'-di-(halo-lower-alkanoyl)-diamines of Formulas I and II where the halo-lower-alkanoyl substituents are the same are prepared by reacting, respectively, the corresponding diamine of Formula III

(III)

40 or of Formula IV

(IV)

where Y in each of Formulas III and IV has the meaning given above for Formulas I and II and where X₁ and X₂ are defined as above for Formula II, with two molar equivalent quantities of a halo-lower-alkanoylating agent derived from an acid of the formula Ac₁—OH. Found particularly useful as halo-lower-alkanoylating agents were halo-alkanoyl halides of the formula Ac₁-halogen and lower-alkyl halo-alkanoates of the formula Ac₁—O—(lower-alkyl) where Ac₁ has the meaning given above for Formulas I and II and the lower-alkyl portion of the ester is preferably methyl, but, can have from one to six carbon atoms, e.g., ethyl, isobutyl, n-hexyl, and the like. The halo radical attached to the carbonyl of the acyl halide is preferably chloro; however, other halo radicals, i.e., bromo, iodo or fluoro, also can be used.

When a halo-lower-alkanoyl halide is used as the halo-acylating agent, the reaction is carried out preferably below room temperature, e.g., between 0°—10° C., and preferably in the presence of an acid acceptor, e.g., NaOH, triethylamine, etc., to take up the hydrogen halide formed by the reaction. The halo-alkanoyl halides are preferred acylating agents, in particular, in the reaction with the compounds of Formula III.

When a lower-alkyl halo-lower-alkanoate is used as the halo-acylating agent, the reaction is run at room tem-

perature or by warming the reactants, if necessary, at a temperature of about 50° to 100° C.

In the preparation of a di-(chloroformamide), i.e., where Ac_1 is chloroformyl, the di-piperidine, preferably as its dihydrochloride is reacted with phosgene while suspended in a nonpolar solvent, e.g., toluene, as illustrated by the preparation of 1,6-bis(N-chloroformyl-2-piperidyl) hexane or 1,6-bis[N-(2-chloroformamidoethyl)-2-piperidyl]hexane by bubbling phosgene into a stirred refluxing suspension of 1,6-bis(2-piperidyl)hexane or 1,6-bis[N-(2-aminoethyl)-2-piperidyl]hexane, respectively.

The N,N'-di-(halo-alkanoyl)-diamines of Formulas I and II where the halo-alkanoyl substituents are different are prepared stepwise by first reacting the diamine of Formula III or IV with one molar equivalent of one halo-alkanoylating agent and then reacting the resulting mono-acylated compound with one molar equivalent of a different halo-alkanoylating agent.

The intermediate bis(piperidyl)alkanes of Formula III are generally known compounds which are readily prepared by known procedures. The intermediate bis(N-aminoalkylpiperidyl)alkanes of Formula IV are novel compounds which are prepared by the procedure described hereinbelow in the specific exemplary disclosure.

The chemical structures of my novel compounds are established by the modes of syntheses and corroborated by the correspondence of calculated and found values for elemental analyses for representative examples.

The following examples will further illustrate specific embodiments of the invention without, however, limiting it thereto.

Example 1

1,6-bis(N-dichloroacetyl-2-piperidyl)hexane: A solution containing 12.6 g. of 1,6-bis(2-piperidyl)hexane and 150 cc. of ethylene dichloride was cooled in an ice bath to 0° C. and to this solution was added dropwise, keeping the temperature below 5° C. during addition, a solution containing 17.6 g. of dichloroacetyl chloride in 50 cc. of ethylene dichloride and sufficient 10% aqueous sodium hydroxide solution to keep the reaction mixture basic. After the addition had been completed, the reaction mixture was stirred for one hour in the ice bath and then for an additional hour at room temperature. The layers were separated; the ethylene dichloride layer was washed successively with dilute aqueous hydrochloric acid, sodium bicarbonate solution and water; it was then dried over anhydrous sodium sulfate, filtered, and concentrated in vacuo to remove the solvent. The residual material was dissolved in benzene and the resulting solution then passed through a column (2 cm. by 50 cm.) of an activated magnesium silicate (Florisil®). The resulting solution was concentrated in vacuo to remove the solvent and the residual material dried in vacuo (0.5 mm.) with warming for about three hours and then cooled to yield a solid material. A small quantity of the solid was triturated with ethyl acetate to yield a white solid. The remainder of the solid was dissolved in hot ethyl acetate, the seed crystals added and the mixture allowed to stand. The solid that separated was recrystallized from ethyl acetate to yield 5.9 g. of the product, 1,6-bis(N-dichloroacetyl-2-piperidyl)hexane, M.P. 132.6-137.8° C. (corr.).

Analysis.—Calcd. for $C_{20}H_{34}Cl_2N_2O_2$: C, 50.63; H, 6.80; Cl, 29.90. Found: C, 50.95; H, 7.12; Cl, 29.55.

1,6-bis(N-dichloroacetyl-2-piperidyl)hexane when administered orally to hamsters infected with *Endamoeba criceti* was found to have an ED_{50} of 1.77±0.25 mg./kg./day, ED_{50} meaning the effective dose necessary to clear 50% of the hamsters of the amebic infection.

Following the above procedure but substituting for dichloroacetyl chloride molar equivalent quantities of dibromoacetyl bromide, diiodoacetyl chloride, difluoroacetyl chloride, bromochloroacetyl chloride, 2,2-dibromopropanoyl bromide, 2,3-dichloropropanoyl chloride, or 2,2-di-

chlorobutanoyl chloride, the following compounds are prepared:

1,6-bis(N-dibromoacetyl-2-piperidyl)hexane,
1,6-bis(N-diiodoacetyl-2-piperidyl)hexane,
1,6-bis(N-difluoroacetyl-2-piperidyl)hexane,
1,6-bis(N-bromochloroacetyl-2-piperidyl)hexane,
1,6-bis(N-2,2-dibromopropanoyl-2-piperidyl)hexane,
1,6-bis(N-2,3-dichloropropanoyl-2-piperidyl)hexane or
1,6-bis(N-2,2-dichlorobutanoyl-2-piperidyl)hexane,
respectively.

Following the above procedure but substituting for 1,6-bis(2-piperidyl)hexane molar equivalent quantities of

15 1,4-bis(2-piperidyl)butane,
1,4-bis(2-piperidyl)hexane,
1,8-bis(2-piperidyl)octane,
1,6-bis(3-piperidyl)hexane,
1,6-bis(4-piperidyl)hexane,
1-(2-piperidyl)-6-(4-piperidyl)hexane,
20 1,6-bis(3,6-dimethyl-2-piperidyl)hexane or
1-(2-piperidyl)-6-(3-piperidyl)hexane,

the following compounds are prepared:

1,4-bis(N-dichloroacetyl-2-piperidyl)butane,
1,4-bis(N-dichloroacetyl-2-piperidyl)hexane,
1,8-bis(N-dichloroacetyl-2-piperidyl)octane,
1,6-bis(N-dichloroacetyl-3-piperidyl)hexane,
1,6-bis(N-dichloroacetyl-4-piperidyl)hexane,
25 1-(N-dichloroacetyl-2-piperidyl)-6-(N-dichloroacetyl-4-piperidyl)hexane,
1,6-bis(N-dichloroacetyl-3,6-dimethyl-2-piperidyl)hexane or
1-(N-dichloroacetyl-2-piperidyl)-6-(N-dichloroacetyl-3-piperidyl)hexane,

respectively.

Example 2

40 1,6-bis(N-chloroacetyl-2-piperidyl)hexane was prepared following the procedure described in Example 1 using 10.2 g. of 1,6-bis(2-piperidyl)hexane in 100 cc. of ethylene dichloride, 11.3 g. of chloroacetyl chloride in 50 cc. of ethylene dichloride, and an excess of 10% aqueous sodium hydroxide solution. The layers of the 45 reaction mixture were separated. The ethylene dichloride layer was washed successively with dilute aqueous hydrochloric acid and water; it was then concentrated in vacuo to remove the solvent whereupon there was obtained a yellow oil which crystallized on standing. This material was triturated with ethyl acetate and collected to yield 3.5 g. of the product, 1,6-bis(N-chloroacetyl-2-piperidyl)hexane, M. P. 87.0-91.0° C. (corr.).

Analysis.—Calcd. for $C_{20}H_{34}Cl_2N_2O_2$: C, 59.25; H, 8.45; Cl, 17.49. Found: C, 59.29; H, 8.23; Cl, 17.56.

50 1,6-bis(N-chloroacetyl-2-piperidyl)hexane when administered orally to hamsters infected with *Endamoeba criceti* was found to have an ED_{50} of 1.46±0.17 mg./kg./day.

55 Following the above procedure but substituting for chloroacetyl chloride molar equivalent quantities of bromoacetyl bromide, iodoacetyl chloride, fluoroacetyl chloride, 2-chloropropanoyl chloride, 2-bromopropanoyl bromide, 3-chloropropanoyl chloride, 2-chlorobutanoyl chloride or 4-chlorobutanoyl chloride, there are obtained the following compounds:

60 1,6-bis(N-bromoacetyl-2-piperidyl)hexane,
1,6-bis(N-iodoacetyl-2-piperidyl)hexane,
1,6-bis(N-fluoroacetyl-2-piperidyl)hexane,
1,6-bis(N-2-chloropropanoyl-2-piperidyl)hexane,
1,6-bis(N-2-bromopropanoyl-2-piperidyl)hexane,
70 1,6-bis(N-3-chloropropanoyl-2-piperidyl)hexane,
1,6-bis(N-2-chlorobutanoyl-2-piperidyl)hexane or
1,6-bis(N-4-chlorobutanoyl-2-piperidyl)hexane,
75 respectively.

Example 3

1,3-bis(N-dichloroacetyl-2-piperidyl)propane: To a solution containing 10.5 g. of 1,3-bis(N-2-piperidyl)propane, 10.1 g. of triethylamine and 150 cc. of chloroform was added over a fifteen minute period with stirring a solution containing 16.1 g. of dichloroacetyl chloride in 50 cc. of chloroform. The reaction mixture was stirred for one hour at room temperature; washed successively with water, dilute aqueous hydrochloric acid, aqueous sodium bicarbonate solution and water; and then concentrated in vacuo to yield an orange oily material. Thin layer chromatography (TLC) on silica gel plates showed four spots in 80% chloroform-20% ether, I_2 developer. A silica-gel column (150 g./50 $\times$ 2.5 cm.) was prepared using 80% chloroform-20% ether. Three 500 cc. fractions were collected and each concentrated in vacuo to remove the solvent. The TLC plate on the first fraction showed it to be homogenous; on standing, the oil from this fraction crystallized and was then recrystallized from a minimum amount of ethyl acetate to yield 3.0 g. of the product, 1,3-bis(N-dichloroacetyl-2-piperidyl)propane, M.P. 146.2-148.0° C. (corr.).

Analysis.—Calcd. for $C_{17}H_{26}Cl_4N_2O_2$: C, 47.24; H, 6.06; Cl, 32.82. Found: C, 47.32; H, 6.23; Cl, 33.18.

1,3-bis(N-dichloroacetyl-2-piperidyl)propane when administered orally to hamsters infected with *Endamoeba criceti* was found to have an ED_{50} of 7.4 ± 2.2 mg./kg./day.

Example 4

1,3-bis(N-chloroacetyl-2-piperidyl)propane was prepared following the procedure described in Example 3 using 10.5 g. of 1,3-bis(2-piperidyl)propane and 10.1 g. of triethylamine in 150 cc. of chloroform, 12.4 g. of chloroacetyl chloride in 50 cc. of chloroform, and six 500 cc. fractions of 80% chloroform-20% ether in the chromatographic separation. The first three 500 cc. fractions were combined and the solvent removed in vacuo with warming to yield 10.1 g. of the product, 1,3-bis(N-chloroacetyl-2-piperidyl)propane, a yellow oil, $n_D^{25} = 1.5288$.

Analysis.—Calcd. for $C_{17}H_{28}Cl_2N_2O_2$: C, 56.20; H, 7.77; Cl, 19.52. Found: C, 56.50; H, 7.84; Cl, 19.31.

1,3-bis(N-chloroacetyl-2-piperidyl)propane when administered orally to hamsters infected with *Endamoeba criceti* was found to clear 5 out of 5 of the animals at a dose level of 25 mg./kg./day.

Example 5

1,6-bis[N-(2-dichloroacetamidoethyl)-2-piperidyl]hexane was prepared as follows: To 4.0 g. of 1,6-bis[N-(2-aminoethyl)-2-piperidyl]hexane was added 3.5 g. of methyl dichloroacetate whereupon an exothermic reaction took place. The reaction mixture was cooled; the viscous oil that separated crystallized and was collected. The crystalline material was recrystallized twice from isopropyl alcohol, using decolorizing charcoal each time, and dried at 60° C. at 20 mm. for eighteen hours to yield 4.1 g. of the product, 1,6-bis[N-(2-dichloroacetamidoethyl)-2-piperidyl]hexane, M.P. 104.4-105.6° C. (corr.).

Analysis.—Calcd. for $C_{24}H_{42}Cl_4N_4O_2$: N, 9.99; Cl, 25.31. Found: N, 10.07; Cl, 25.39.

1,6-bis[N-(2-dichloroacetamidoethyl)-2-piperidyl]hexane when administered orally to hamsters infected with *Endamoeba criceti* was found to clear 4 out of 5 (75% corrected, controls 1 out of 5) at 25 mg./kg./day.

The above compound is also obtained by following the procedure of Example 1 using 1,6-bis[N-(2-aminoethyl)-2-piperidyl]hexane and dichloroacetyl chloride as the reactants. Using chloroacetyl chloride, trichloroacetyl chloride, 2,2-dibromopropanoyl bromide or 2,2-dichlorobutanoyl chloride in place of dichloroacetyl chloride yields, respectively,

1,6-bis[N-(2-chloroacetamidoethyl)-2-piperidyl]hexane,
1,6-bis[N-(2-trichloroacetamidoethyl)-2-piperidyl]hexane,
5 1,6-bis[N-(2-(2,2-dibromopropanamido)ethyl)-2-piperidyl]hexane or
1,6-bis[N-(2-(2,2-dichlorobutanamido)ethyl)-2-piperidyl]hexane.

The above intermediate 1,6-bis[N-(2-aminoethyl)-2-piperidyl]hexane was prepared in two steps as follows:

10 To 42.2 g. of 1,6-bis(2-piperidyl)hexane was added slowly 30 g. of glycolonitrile (70%) whereupon an exothermic reaction took place. The reaction mixture was allowed to stand for thirty minutes, heated on a steam bath for two hours and then poured into water. The solid that separated was collected, air dried, and recrystallized twice from isopropyl alcohol, using decolorizing charcoal each time, and dried at 60° C. and 20 mm. for eighteen hours to yield 39.7 g. of 1,6-bis(N-cyanomethyl-2-piperidyl)hexane, M.P. 98-101° C.

20 Analysis.—Calcd. for $C_{20}H_{34}N_4$: N, 16.95. Found: N, 16.96.

To 11.4 g. of lithium aluminum hydride was added 250 cc. of tetrahydrofuran; the mixture was stirred for thirty minutes; and then 39.7 g. of 1,6-bis(N-cyanomethyl-2-piperidyl)hexane dissolved in 350 cc. of tetrahydrofuran was added dropwise with stirring maintaining a slow reflux. After completion of the addition, the reaction mixture was refluxed gently on a steam bath for six and one half hours and then allowed to stand at room temperature overnight. To the reaction mixture was added 12 cc. of water dropwise with stirring, maintaining a slow reflux, followed by addition of 70 cc. of a saturated solution of potassium sodium tartrate added dropwise, maintaining the slow reflux. The mixture was cooled in ice, filtered through infusorial earth and the filter aid washed with tetrahydrofuran. The filtrate was evaporated to remove the solvent, thereby yielding 38.8 g. of a yellow oily material. Thirty grams of the oily material was distilled in vacuo yielding the following fractions: (1) 1.3 g., $n_D^{28} = 1.5038$, B.P. 116-138° C. at 0.15 mm.; (2) 8.8 g., $n_D^{28} = 1.5025$, B.P. 138-171° C. at 0.15 mm.; and (3) 13.2 g., $n_D^{28} = 1.5032$, B.P. 171-173° C. These three fractions of 1,6-bis[N-(2-aminoethyl)-2-piperidyl]hexane, totaling 23.3 g., were combined and analyzed.

Analysis.—Calcd. for $C_{20}H_{42}N_4$: N, 16.54. Found: N, 16.37.

Following the above procedure for the preparation of 1,6-bis[N-(2-dichloroacetamidoethyl)-2-piperidyl]hexane but substituting for 1,6-bis[N-(2-aminoethyl)-2-piperidyl]hexane molar equivalent quantities of

55 1,3-bis[N-(2-aminoethyl)-2-piperidyl]propane,
1,8-bis[N-(2-aminoethyl)-2-piperidyl]octane,
1,6-bis[N-(3-aminopropyl)-2-piperidyl]hexane,
1,6-bis[N-(4-aminobutyl)-3-piperidyl]hexane,
1-[N-(2-aminoethyl)-2-piperidyl]-6-[N-(2-aminoethyl)-3-piperidyl]hexane or
1,4-bis[N-(6-aminohexyl)-2-piperidyl]butane,

60 the following compounds are prepared:

1,3-bis[N-(2-dichloroacetamidoethyl)-2-piperidyl]propane,
1,8-bis[N-(2-dichloroacetamidoethyl)-2-piperidyl]octane,

65 1,6-bis[N-(3-dichloroacetamidopropyl)-2-piperidyl]hexane,
1,6-bis[N-(4-dichloroacetamidobutyl)-3-piperidyl]hexane,

1-[N-(2-dichloroacetamidoethyl)-2-piperidyl]-6-[N-(2-dichloroacetamidoethyl)-3-piperidyl]hexane or
1,4-bis[N-(6-dichloroacetamidohexyl)-2-piperidyl]butane, respectively.

The above intermediate di-[N-(aminoalkyl)-piperidyl]alkanes are prepared by following the above-described

two-step procedure for the preparation of 1,6-bis[N-(2-aminoethyl)-2-piperidyl]hexane and substituting in the first step, the appropriate di-(piperidyl)-alkane for 1,6-bis (2-piperidyl)hexane and, for the compounds other than the di-[N-(2-azinoethyl)-piperidyl]-alkanes, the appropriate chloro(or bromo)-alkanenitrile for glycolonitrile, and preferably using an acid-acceptor, e.g., sodium hydroxide solution, to take up the hydrogen halide formed by the reaction, and then, in the second step, reducing the resulting di-(N-cyanoalkylpiperidyl)-alkane with lithium aluminum hydride. For example, 1,8-bis[N-(2-aminoethyl)-2-piperidyl]octane is formed by reacting 1,8-bis(2-piperidyl)octane with glycolonitrile and reducing the resulting 1,8-bis[N-(cyanomethyl)-2-piperidyl]octane; 1,6-bis[N-(4-aminobutyl)-3-piperidyl]hexane is formed by reacting 1,6-bis(3-piperidyl)hexane with 4-bromobutane-nitrile (γ -bromobutyronitrile) and reducing the resulting 1,6-bis[N-(3-cyanopropyl)-3-piperidyl]hexane; and 1,4-bis[N-(6-aminoheptyl)-2-piperidyl]butane is formed by reacting 1,4-bis(2-piperidyl)butane with 6-chlorohexane-nitrile and reducing the resulting 1,4-bis[N-(5-cyanopentyl)-2-piperidyl]butane.

Example 6

1,6-bis(N-trichloroacetyl-2-piperidyl)hexane was prepared following the procedure described in Example 2 using 10.2 g. of 1,6-bis(2-piperidyl)hexane in 100 cc. of ethylene dichloride, 18.1 g. of trichloroacetyl chloride in 50 cc. of ethylene dichloride, and an excess of 10% aqueous sodium hydroxide solution. There was thus obtained 7.8 g. of the product, 1,6-bis(N-trichloroacetyl-2-piperidyl)hexane, M.P. 150.6-152.0° C. (corr.), after two recrystallizations from ethyl acetate.

Analysis.—Calcd. for $C_{20}H_{30}Cl_3N_2O_2$: C, 44.22; H, 5.57; N, 5.16. Found: C, 44.54; H, 5.78; N, 5.22.

1,6-bis(N-trichloroacetyl-2-piperidyl)hexane when administered orally to hamsters infected with *Endamoeba criceti* was found to clear 5 out of 5 of the animals at a dose level of 200 mg./kg./day.

Following the above procedure but using a molar equivalent quantity of tribromoacetyl chloride, 2,2,3-trichloropropanoyl chloride or 2,3,4-trichlorobutanoyl chloride in place of trichloroacetyl chloride, the following compounds are formed: 1,6-bis(N-tribromoacetyl-2-piperidyl)hexane, 1,6-bis(N-2,2,3-trichloropropanoyl-2-piperidyl)hexane or 1,6-bis(N-2,3,4-trichlorobutanoyl-2-piperidyl)hexane, respectively.

The amebacidiadly active compounds of my invention, as illustrated in the foregoing examples, were administered orally in aqueous suspension to the infected hamsters. They can also be administered in solid form, e.g., as tablets or in capsules, and optionally admixed with conventional excipients, e.g., starch, talc, and the like.

I claim:

1. A di-piperidine of the formula

where Y is alkylene having from three to eight carbon atoms between its connecting linkages, and, Ac_1 and Ac_2 are each halo-lower-alkanoyl having from one to four carbon atoms and from one to three halogen atoms.

2. 1,6-bis(N-dichloroacetyl-2-piperidyl)hexane.
3. 1,6-bis(N-chloroacetyl-2-piperidyl)hexane.
4. 1,3-bis(N-dichloroacetyl-2-piperidyl)propane.
5. 1,3-bis(N-chloroacetyl-2-piperidyl)propane.
6. 1,6-bis(N-trichloroacetyl-2-piperidyl)hexane.
7. A di-piperidine of the formula

where Y is alkylene having from three to eight carbon atoms between its connecting linkages, X_1 and X_2 are each lower-alkylene having from two to six carbon atoms and having at least two carbon atoms between its connecting linkages, and, Ac_1 and Ac_2 are each halo-lower-alkanoyl having from one to four carbon atoms and from one to three halogen atoms.

8. 1,6-bis[N-(2-dichloroacetamidoethyl)-2-piperidyl]hexane.

No references cited.

UNITED STATES PATENT OFFICE
CERTIFICATE OF CORRECTION

Patent No. 3,277,101

October 4, 1966

Alexander R. Surrey

It is hereby certified that error appears in the above numbered patent requiring correction and that the said Letters Patent should read as corrected below.

Column 2, line 15, for "diidoacetyl" read -- diiodoacetyl --; column 6, lines 26 and 44, for "piperdy1", each occurrence, read -- piperidyl --; column 7, line 2, for "2-aminoethyl)" read -- (2-aminoethyl) --; column 8, line 32, the left-hand portion of the formula should appear as shown below instead of as in the patent:

Signed and sealed this 12th day of September 1967.
